1 Claim

ABSTRACT OF THE DISCLOSURE

A generally semicircular needle for piercing flesh and guiding a blunt epidural needle into operative position in the epidural space for the purpose of administering anesthetic.

BACKGROUND

The surgical technique wherein epidural anesthesia is employed has been known for a considerable period of time. This technique has not however enjoyed widespread use because of the lack of adequate instruments to carry out this procedure. U.S. Patent No. 2,952,256, patented to T. J. Meader et al. Sept. 13, 1960, and U.S. Patent No. 2,922,420, patented to Peter Aiming Cheng Jan. 26, 1960, disclose certain instruments for use in epidural anesthesia. The devices disclosed by these patentees employ blunt needles. These blunt needles require some means of introducing them into the patient's back. This introducing means must of necessity be some sharp instrument which precedes the epidural needle of patentees into the patient's back. In the use of two instruments it is necessary that great care be taken to avoid pieces of flesh being torn off and forced into the epidural or subarachnoid spaces. The consequences of dragging such pieces of flesh into either of these spaces may be very serious.

SUMMARY

The present invention relates to an introducer needle for use in conjunction with blunt epidural needles whereby the possibility of dragging flesh into the epidural or subarachnoid spaces is substantially eliminated. The introducer needle is an elongated puncturing member with a generally semicircular cross section. The walls of the puncturing member define a channel longitudinally thereof. The outer end of the puncturing member is provided with a cutting edge and in general tapers to a point to facilitate its insertion through flesh. Once this introducer needle has been inserted into the patient's back the channel is adapted to receive and guide a blunt epidural needle into the epidural space. This introducer needle is provided with a grip or handle which is positioned on the puncturing member a predetermined distance back from the outer end of the puncturing member. This predetermined distance limits the depth to which the puncturing member may be inserted in a patient's back. The grip is located at a convenient angle and provided with a convenient configuration to facilitate the grasping of this element by the technician using it.

BRIEF DESCRIPTION OF THE DRAWINGS

For a more detailed understanding of the invention reference is made to the accompanying drawing in which:

2

FIGURE 1 is a perspective view of the introducer needle of this invention;

FIGURE 2 is a plurality of cross sectional views of various embodiments of the puncturing member;

FIGURE 3 is a front elevation of the introducer needle;

FIGURE 4 is a side elevation of the introducer needle, in cross-section; and

FIGURE 5 is a plan view of the introducer needle.

In the embodiment of this invention depicted in the drawings an elongated puncturing member indicated generally at 10 is shown to be a generally semicircular shaft having wall 12 which is arcuate in cross section, the longitudinal edges of which are not sharp. Wall 12 defines by its inner surface a channel 14. The elongated puncturing member 10 is provided with an outer end indicated generally at 16 which is tapered and beveled forwardly and downwardly from the open side of channel 14. Outer end 16 is provided with a cutting edge 18 which extends completely around the beveled portion of outer end 16. At the extreme end of outer end 16 a point 19 is provided. A means for grasping the introducer needle is provided. This means for grasping comprises a grip indicated generally at 20. Grip 20 extends from puncturing member 10 at an included angle with said outer end of more than about 90°. A platform 24 is provided which serves as a support to which wall 12 of elongated puncturing member 10 may be secured. A straight shank 26 projects angularly from puncturing member 10. This straight shank portion 26 merges into arcuate shank portion 28 which has a generally S-shaped curve. Several of the arcuate cross sections which elongated puncturing member 10 may assume are illustrated in FIGURE 2. A shallow disc-shaped cross section is illustrated at 30. A U-shaped cross section is illustrated at 32. At 34 a C-shaped cross section is illustrated. The C-shaped cross section is of such configuration that the blunt epidural needle could not escape from the introducer needle through the open side of the channel. At 36 a rectangular cross section is illustrated and in FIGURE 3 a semicircular cross section is illustrated at 38.

In use the technician administering the epidural anesthetic grasps the introducer needle in one hand generally with his index finger on the front of the grip below the puncturing member in the general area of straight shank portion 26, the middle finger on the front of the grip below the index finger in the area of arcuate shank portion 28, and the thumb on the rear of the grip below the platform 24. The puncturing member is forced into the patient's back and when inserted to the desired depth the blunt epidural needle is placed in the channel 14 and inserted into the patient's back. When the epidural needle has been inserted to the desired depth of penetration, the introducer needle is withdrawn and the anesthetic procedure is carried out as described in Cheng 2,922,420.

The elongated puncturing member 10 is generally a stainless steel hypodermic tube which has been divided in half along its longitudinal axes. Conveniently the stainless steel hypodermic tube is about thirteen gauge in size.

What has been described are preferred embodiments in which modifications and changes may be made without departing from the spirit and scope of the accompanying claim.

What is claimed is:

1. An anesthetic device comprising:
 an elongated puncturing member having a generally
 semicircular cross section, the wall of said member
 defining a channel extending longitudinally of said
 member, the outer end of said member being tapered
 forwardly and provided with a cutting edge;
 5
 a grip attached to said member at a predetermined dis-
 tance from said cutting edge, said grip extending
 from said member at an included angle with said
 outer end of more than about 90°, said channel open-
 ing away from said grip, said grip comprising a
 straight shank portion extending outwardly from said
 member and an arcuate shank portion extending in
 a generally S-shaped curve from the lower end of 15
 said straight shank portion.
